Anthony L. Passafaro, Fredonia, Clarence J. Braun, Dunkirk, and William K. Powers, Fredonia, N. Y., assignors to Allegheny Ludlum Steel Corporation, Brackenridge, Pa., a corporation of Pennsylvania

Application January 10, 1957, Serial No. 633,492

8 Claims. (Cl. 51—39)

This invention relates to billet grinders and in particular to apparatus for effecting an automatic and progressively continuous grinding of billets of steel.

In industry and in particular the steel mill industry, billets of steel must be conditioned to remove surface and edge defects therefrom so that the billets may be further processed into sheet and strip products. Heretofore such surface and edge defects have been removed by surface grinding as by means of a manually operated swing grinder, such operation requiring a considerable number of swing grinders in constant operation in order to maintain production rates. Even with the swing grinders, it has been quite difficult to remove edge defects from the billets, such operation being time consuming. Thus a considerable capital investment in equipment must be maintained while considerable manpower must be allocated to operate the swing grinders in order to maintain an adequate rate of conditioned billets with the result that the conditioning of billets is an expensive production item.

Many attempts have been made heretofore to alleviate the expensive operation of conditioning billets by finding a more efficient mode for effecting the conditioning. These attempts have all failed, however, because the substantially square cross-sectional shape of the billets has heretofore made it impossible to efficiently and automatically effect the grinding of the corners or edges and flat sides of the billet in a continuous operation.

An object of this invention is to provide grinding apparatus for efficiently effecting the progressive automatic grinding of a billet to produce a billet having ground corners or edges and flat surfaces.

Another object of this invention is to provide, in a billet grinding apparatus, means for supporting and rotatably advancing a billet while engaged by a grinding wheel for effecting a progressive grinding of all of the surfaces of a billet.

A further object of this invention is the provision, in a billet grinding apparatus, of rotatable drive supporting means with means for effecting a positive actuation of the rotatable drive to rotatably advance the billet when engaged by a grinding means and means for controlling the positive actuation to provide an intermittent operation of the rotatable drive whereby the grinding means engages and grinds an edge of the billet for a period of time substantially equal to the period of time of grinding a flat surface thereof.

A still further object of this invention is the provision in a billet grinding machine for progressively grinding a billet, of means for rotatably advancing the billet as the billet is ground, means for effecting movement of the grinder relative to the billet, and means for controlling the pressure of the grinder on the billet whereby a substantially uniform grinding pressure is applied to the corners or edges and flat surfaces of the billet as the billet is rotatably advanced.

Other objects of this invention will become apparent

2

from the following description when taken in conjunction with the accompanying drawings in which:

Figure 1 is a view in side elevation of a portion of a billet grinding apparatus embodying features of this invention;

Fig. 2 is a view in side elevation of a part of the apparatus of Fig. 1 and of the drive for such apparatus;

Fig. 3 is a view in end elevation and greatly enlarged of the billet grinding apparatus taken along the line III—III 10 of Fig. 2;

Fig. 4 is a view in section and greatly enlarged of one of the rotatable supports of the apparatus of Fig. 1 as taken along the line IV—IV of Fig. 5;

Fig. 5 is a view, partly in section, of one of the rotatable supports taken along the line V—V of Fig. 4;

Fig. 6 is a view in side elevation of the supporting mechanism for a grinding wheel utilized in conjunction with the apparatus illustrated in Figs. 1 and 2 and of the schematic diagram of the control circuits for controlling the movement and grinding pressure of the grinding wheel; and

Fig. 7 is a view in top elevation of a portion of the supporting mechanism of the grinding wheel.

Referring to the drawing, the billet grinding apparatus 25 of this invention comprises the billet supporting apparatus shown generally at 10 in Fig. 1, the drive apparatus shown generally at 12 in Fig. 2 and the grinding wheel support and controls shown generally at 14 in Fig. 6. As illustrated in Fig. 1, the billet supporting apparatus 10 in general comprises two fixed housings 16 and 18 disposed in spaced relation on a suitable foundation or floor 20. In this instance the housings 16 and 18 are identical and in general comprise vertically disposed frame plate members 22, 24 and 26, the upper ends of

35 which are held in spaced relation by suitable tie rods 28, pipe spacer members 30, illustrated in Fig. 4, being disposed about the tie rods 28 to abut against the spaced frame plate members and maintain such plate members in spaced position relative to one another. The spaced frame plate members 22, 24 and 26 are suitably mounted on and with their lower ends secured to a base member 32 supported on spaced legs 34 and 36 which are seated on and secured in any suitable manner to the foundation 20. The fixed housings 16 and 18 are mounted as illustrated in Fig. 1 in spaced relation to provide a space therebetween for receiving a grinding wheel 38 for engaging a billet 40 as will be referred to hereinafter.

Each of the fixed housings 16 and 18 is provided with a pair of rotatable housings 42 and 44 disposed between the frame plate members 22—24 and 24—26, respectively. The assembly and mounting for the rotatable housing 42 is better illustrated in Fig. 4 of the drawing, to which reference may be made.

As illustrated in Fig. 4, the rotatable housing 42, the details of which will be referred to hereinafter, is carried for rotatable movement by rotatable members supported in suitable openings in frames 22 and 24. Thus a main gear member 46 is provided with the web of the gear adjacent the frame 22 and having a hub 48 disposed to extend into an opening in the frame plate 22. A suitable roller bearing structure 50 is disposed about the hub 48 and is held in operative position in the opening in the frame plate 22 as by means of the bearing plate 52 which is secured to the frame plate 22 as by means of the stud screws 54 and a ring plate 53 secured to the bearing plate 52 as by means of stud screws 55. Any suitable roller bearing structure may be utilized in this construction for providing sufficient bearing support for the drive gear 46.

In practice the opening in the hub 48 of the drive gear 46 is provided with a protective sleeve 56 held in position as by means of a flange ring 58 which is secured to the hub by spaced screws 59.

The support for the rotatable housing 42 as well as the rotatable housing 44 in the center frame plate 24 is formed of a spacer pipe member 60 disposed for rotation relative to a bushing 62 carried in the opening of the frame plate 24, the opposite ends of the spacer pipe 60 being threaded on the outer surface thereof for receiving a threaded flange member 64, the purpose of which will be explained more fully hereinafter.

In order to provide for retention of the bushing 62 as well as to provide a positive drive for certain of the components of the rotatable housings 42 and 44 as will be explained more fully hereinafter, a gear member 66 is positioned on each side of the flange plate 24 being spaced therefrom as by spacer rings 68 with the webs of the gear members 66 overlapping the bushing 62 to hold the same in position, the gears 66 on opposite sides of the flange plate 24 being secured in position as by means of spaced tie bolts 70 extending through the gears 66, spacer rings 68 and the flange plate 24. The gears 66 are thus maintained in fixed position on the frame plate 24, the reason for which will be explained more fully hereinafter.

As stated hereinbefore, each of the rotatable housings 42 and 44 of each of the fixed housings 16 and 18 is identical, although disposed in reverse relation with respect to one another. Thus, as illustrated in Figs. 4 and 5, the rotatable housing 42 is formed of a rugged rectangular box frame member 72, the sides of which have substantial cross bar or plate members 74-76, 78-80 at the upper and lower ends thereof being spaced as by means of the upper end plate 82 and the lower end plate 84 and being disposed to be secured to the web of the drive gear 46 and the flange plate 64 as by means of suitably spaced stud screws 86 and 87, respectively, as shown more fully in Fig. 4. The housings 42 and 44 being identically mounted are thus disposed to be simultaneously driven as the drive gear 46 associated with each housing is operated as will be described hereinafter.

In order to support a billet 40 along its longitudinal axis in the aligned openings in the assembled rotatable housings 42 and 44 of each of the fixed housings 16 and 18, each of the rotatable housings is provided with a pair of grooved feed rollers or wheel members 88 and 90 mounted in the housings in aligned relation with the grooves of each pair of wheel members 88 and 90 facing one another in aligned relation, it being noted that the grooves of each pair of wheel members 88 and 90 are also aligned with the openings formed by the sleeves and spacer pipe member 60 of each of the fixed housings 16 and 18.

The grooved wheel 90 is fixedly mounted in the housing 42 as better illustrated in Fig. 5. Thus the grooved wheel member 90 is fixed to a shaft 92 in any suitable manner, the ends of the shaft 92 being disposed to extend through suitable cartridge bearing assemblies 94 disposed in openings therefor in the opposite sides of the frame of the housing 42. The details of the cartridge bearings need not be described, as they are well known in the art and can be purchased as a commercial commodity ready for mounting for supporting a given shaft. As illustrated in Fig. 5, one end of the shaft 92 extends beyond the frame of the housing 42 at one side thereof and carries a sprocket gear 96 thereon, and the other end of the shaft 92 extends beyond the frame of the housing 42 at the other side thereof and carries a worm gear 98 thereon.

Grooved wheel member 88 is similar to the grooved wheel member 90, being mounted on a shaft 100 which extends through suitable cartridge bearing assemblies 102 at the opposite ends thereof, such cartridge bearing assemblies being carried in movable bearing block support members 104 and 106 on the opposite sides of the frame of the housing 42 for slidable movement between side cross-bar or plate members 74 and 78 thereof. The bearing support members 104 and 106 are thus movable vertically within the housing 42 for adjusting or position-

ing the grooved wheel member 88 relative to the grooved wheel member 90 for accommodating different sized billets 40 therebetween as the billets are longitudinally moved through the aligned openings in the rotatable housings 42 and 44 of the fixed housings 16 and 18. In order to support the grooved wheel member 88 in its operative position, a pair of spaced spring members 108 and 110 as illustrated in Fig. 4 is carried in each side of the frame of the housing 42 disposed between the end plate 82 and the upper end of the respective bearing block support members 104 and 106. Thus one pair of the spring members 108 and 110 have one end of the springs disposed to seat against the upper end of the associated bearing support member 104 or 106, the other end of the springs of each pair being disposed about studs 112 and 113, respectively, to seat against washers 114 and 115, respectively. As illustrated, the studs 112 and 113 extend downwardly from and are carried by the end plate 82, each of the studs being provided with a pair of adjustable nuts 116 and 118 for controlling the positioning of the washers 114 and 115, respectively. By adjusting the nuts 116 and 118 on each of the studs 112 and 113, the force of the springs 108 and 110, respectively, can be adjusted to permit a predetermined displacement of the grooved wheel 88 relative to the fixed grooved wheel 90 to accommodate irregularities in a billet and for maintaining a driving force on a predetermined sized billet 40 disposed therebetween. The movable grooved wheel 88 has one end of its shaft 100 disposed to extend through the bearing support member 104, as illustrated in Fig. 5, to carry a sprocket 120 for cooperating with the sprocket 96 as will be described hereinafter.

Again referring to Fig. 1 of the drawing, the drive for the grooved wheel members 88 and 90 is better illustrated. As stated hereinbefore, the rotatable housings 42 and 44 are identical, but are utilized in reverse position. Thus the drive which will now be described with respect to the housing 44 and is shown on the front of the housing 44 as illustrated in Fig. 1 will have a counterpart on the rear of the housing 42, the parts being in reversed order. Thus a pair of brackets 122 and 124 are disposed in spaced relation on the frame of the housing 44 and are secured thereto in any suitable manner. The brackets 122 and 124 are provided with suitable bearings (not shown) for supporting the shaft 126 of a worm 128, the one end of the shaft 126 having a pinion gear 130 secured thereto with the teeth of the pinion gear 130 in engagement with the teeth of the gear 66 which is carried on and fixed to the center frame plate 24 as described hereinbefore. The worm 128 is disposed in engagement with the teeth of the pinion gear 98 carried by the end of the shaft 92 of the fixed grooved wheel member 90.

Again referring to Fig. 1, a portion of the drive for simultaneously operating the cooperating grooved wheels 88 and 90 of each of the rotatable housings is better illustrated by referring to the showing of the housing 42, it being understood that a similar drive, except for reverse positioning, is provided on the reverse side of the housing 44 shown in Fig. 1. Thus an idler sprocket 132 is mounted on a bracket 134 which is carried on the web of the gear 46, and a take-up sprocket 136 is carried on a bracket 138, pivotally mounted as at 139 to the frame of the housing 42, the sprockets 96, 120, 136 and 132 being disposed to be connected and driven as by a sprocket chain 140 shown in dot-dash outline. As illustrated in Figs. 1 and 5, the bracket 138 is provided with an opening therein for receiving the upper end of a stud 142 for movement therein, the lower end of the stud 142 being carried by a suitable bracket 144 mounted on the frame of the housing 42 and being provided with adjustable nuts 146 and 148 so as to vary the bias of a coil spring 150 disposed between the nut 146 and the pivotal bracket 138 whereby the positioning of the take-up sprocket 136 can be adjusted for maintaining the chain

140 in operative position relative to the drive sprockets 96 and 120 of the grooved wheel members 90 and 88, respectively, to effect a simultaneous drive thereof. The bias of the spring 150 effectively causes the bracket 138 to pivot and move the sprocket 136 to maintain the chain 140 in driving relation with the drive sprockets 96 and 120 as the grooved wheel member 88 is moved as by reason of irregularities on the billet passing between the cooperating drive rolls or grooved wheel members 88 and 90.

In order to effect a simultaneous rotation of the movable housings 42 and 44, the large drive gears 46 rotatably carried adjacent each of the outer frame members 22 and 26 are disposed to engage pinion gears 152 and 154 carried on a shaft 156 which extends through suitable cartridge bearings 158, 160 and 162 in the lower end of the frame plates 22, 24 and 26, respectively, the adjacent ends of the shafts 156 of the fixed housings 16 and 18 being connected through a self-aligning coupling 164 with the end of the shaft 156 extending beyond the fixed housing 18 being disposed to be operated by the drive shown generally at 12 in Fig. 2. Thus the end of the shaft 156 which extends beyond the fixed housing 16 terminates in a pinion gear 166 disposed to be driven by a large drive gear 168 carried on the end of a shaft 170 mounted in suitable bearings (not shown) on the upper end of a bearing frame member 172. The other end of the shaft 170 is provided with a Geneva gear 174 which is suitably keyed to the shaft 170 and is disposed to be engaged by a driver disk 176 carried on the end of a shaft 178 connected through a gear reducer 180 to be driven by any suitable means such as a motor (not shown), or the like.

In the embodiment illustrated in Figs. 2 and 3, the driver disk 176 comprises two spaced wheel members 182 and 184 having a pair of spaced pins 186 and 188 disposed diagonally opposite one another and extending between the spaced wheel members 182 and 184. The spaced pins 186 and 188 are provided with sleeves 190 and 192, respectively, on the outer surfaces thereof, the sleeves being capable of being rotated relative to their supporting pins. The pins 186 and 188 are so disposed that upon rotation of the disk 176 one of the pins will engage a slot of the Geneva gear 174 for effecting a quarter turn of the Geneva gear 174 as the disk 176 is rotated to a point where the pin is released from the slot of the Geneva gear 174. A spacing member 194 is mounted between the spaced wheel members 182 and 184 and is so shaped that it will not interfere with movement of the Geneva gear 174 when one of the pins 186 or 188 engages a slot of the Geneva gear, nor will it effect any movement of the Geneva gear when the pins are out of engagement with the slots of the Geneva gear.

Thus, as the disk member 176 is driven, the rotatable sleeve of one of the pins 186 or 188 engages one of the slots of the Geneva gear 174 and as the disk 176 is rotated, slides inwardly and then outwardly in rotating engagement with a forward edge of the slot to effectively drive the Geneva gear in a counterclockwise direction as viewed in Fig. 3 downwardly to a point where the sleeve carried by the pin disengages the slot of the Geneva gear. No further movement of the Geneva gear will be effected until the following pin engages the following slot of the Geneva gear 174. As the Geneva gear 174 is driven in the manner just described, the large drive gear 168 carried on the other end of shaft 170 is rotated to drive the pinion gear 166 of the coupled shafts 156. As the shafts 156 are rotated, the pinion gears 152 and 154 carried by each of the shafts are actuated to effect an operation of the drive gears 46 associated with each of the rotatable housings 42 and 44 of each of the fixed housings 16 and 18. As the drive gears 46 are actuated, the movable housings 42 and 44 are simultaneously rotated in the same direction, it being noted that the

housings 42 and 44 are rotated relative to the fixed gears 66 carried on opposite sides of the center frame plate 24. Since the worms 128 carried on the one face of each of the movable housings 42 and 44 are coupled 5 through the pinions 130 to the fixed gears 66, the worms 128 are driven to effect a drive of the gear 98 carried on the shaft 92 of the fixed grooved wheel member 90 to effect a clockwise rotation thereof. At the same time the sprocket 96 carried on the other end of the shaft 92 is driven to effectively drive the chain 140 carried over the sprockets 96, 120, 136 and 132 whereby the sprocket 120 of the adjustable grooved wheel 88 is driven to drive the grooved wheel 88 counterclockwise so that the grooved wheels 88 and 90 cooperate to advance a billet 15 which is disposed therebetween. It is to be noted that each of the rotatable housings 42 and 44 of each of the fixed housings 16 and 18 is rotated simultaneously by means of the interconnected gear drive therefor and that the pair of cooperating grooved wheels 88 and 90 of 20 each of the rotatable housings 42 and 44 is operated simultaneously by reason of the interconnected gear drive and sprocket and chain drive therefor. Thus while the rotatable housings 42 and 44 are simultaneously rotated to effect a rotation of the pairs of grooved wheel members about a longitudinal axis through the assembled housings to thereby turn or rotate a billet 40 which is supported by the grooved wheel members, the pairs of grooved wheels 88 and 90 are also operated to turn about their axes in a direction to simultaneously drive and advance the billet 40 through the rotatable housings.

As is self-evident, since the drive 12 of the billet grinding machine is provided with a Geneva gear 174 in the drive thereof, the rotatable movement of the rotatable housings 42 and 44 as well as the drive of the grooved wheel members 88 and 90 of each of the rotatable housings is an intermittent drive, the Geneva gear 174 being correlated with the positioning of the billet 40 between the grooved wheel members 88 and 90 so that as the pin 186 or 188 engages a slot of the Geneva gear a rotation 35 of the billet 40 is obtained with a corner or edge of the billet in engagement with the grinding wheel 38. As the billet 40 is turned to present a flat surface to the grinding wheel 38, the slot of the Geneva gear is disengaged so that no movement of the billet 40 is obtained as the grinding wheel 38 engages a major portion of the flat 40 surface thereof. By thus controlling the rotatable movement of the housings 42 and 44 to effect a rotatable advance of the billet 40, the billet is rotated to present a corner or edge thereof to be ground in a period of time substantially equal to the period of time required for grinding the flat surface of the billet as will be described hereinafter. In practice, with a 4½ inch billet, a time of about two seconds is permitted for grinding each of the flat surfaces and each of the corners or 50 edges of the billet 40, the resulting ground billet having slightly rounded edges as a result of the grinding thereof. As will be evident a suitable coolant (not shown) is supplied to the surfaces of the billet in any suitable manner as the grinding wheel effects a grinding operation thereon.

In order to control the pressure of the grinding wheel 38 on a billet 40 and control movement of the grinding wheel 38 relative to the billet 40 when a flat surface thereof is being ground, the grinding wheel 38, as illustrated in Fig. 6, is carried by a suitable rectangular frame member 194 which is pivotally carried as at 196 on an upright frame or stanchion 198 which, in turn, is pivotally mounted as at 200 on a suitable base 202. The grinding wheel end of the rectangular frame 194 is pivotally connected as by linkage 204 to the frames of the fixed housings 16 and 18 as better shown in Fig. 7. Thus brackets 206 and 208 carried by the fixed housings 16 and 18, respectively, are provided with bearings (not shown) in which the ends of a shaft 209 are mounted. Intermediate of the brackets 206 and 208 there are disposed bearing sleeves 210 and 212 to which are fixedly con-

nected links 214 and 216, respectively, the lower ends of which are provided with bearing sleeves (not shown) for receiving a shaft 218 on which is pivotally mounted an upwardly extending linkage 220, the upper end of which is pivotally carried by a shaft 222 which is mounted in brackets 224 and 226 at the ends thereof and which are carried on the lower surface of the ends of the rectangular frame 194. As illustrated in Fig. 7, a pair of spring members 228 and 230 is disposed about the shaft 209 between the bearing sleeves 210 and bracket 206 and the bearing sleeve 212 and bracket 208, respectively, in order to cushion sideways movement of the frame 194 during a grinding operation. The linkage support 204 effectively supports the grinding wheel 38 during a lateral movement thereof across a flat surface of a billet 40 as the upright frame 198 is pivoted about its pivot 200 as will be referred to hereinafter, as well as during a grinding operation around a corner of the billet. In order to drive the grinding wheel 38 a suitable motor 232 shown in dash outline is carried by the frame 194 in a position above the upright frame 198 and is connected as by means of a belt 234 to a grooved pulley 236 of the grinding wheel 38.

The other end of the frame 194 is pivotally connected as at 238 to the ends of piston rods 240 and 242 connected to the pistons (not shown) of double acting fluid responsive cylinders 244 and 246, respectively, which are pivotally mounted as at 248 and 250, respectively, on a fixed frame 252 disposed adjacent the upright pivotal frame 198. The pivotal frame 198 is also connected as by means of pivotally connected link 254 and lever 256 to the end of a piston rod 258 which is connected to a piston (not shown) of a double acting fluid responsive cylinder 260 which is pivotally connected as at 262 to the fixed frame 252. The lever 256 is pivotally mounted as at 264 in a suitable bracket 266 carried by the top of the fixed frame 252 and the end of the link 254 is pivotally connected as at 268 to a bracket 270 carried by the upright pivotal frame 198. Another double acting fluid responsive cylinder 272 is disposed in a suitable manner as for example as illustrated by pivoting at one end as at 274 to a bracket 276 which is carried by one of the housings 16 or 18 having the piston rod 278 thereof pivotally connected as at 280 to a rod 282 which is pivotally mounted as at 284 to one of the housings 16 or 18 and which carries a roller stop 286 at the other end thereof disposed to engage an adjustable stop member 288 which is carried by the pivotal frame member 198, the purpose of which will be explained more fully hereinafter.

The double acting fluid responsive cylinders 244, 246, 260 and 272 are connected by suitable pipe connections, not shown but which are indicated by the dash arrow lines 290—292, 294—296, 298—300 and 302—304, respectively, to electromagnetically controlled directional valves shown generally at 306, 308, 310 and 312, respectively, each of the valves being connected to a suitable source of supply of fluid pressure such as, for example, air pressure. Each of the control valves 306, 308, 310 and 312 is provided with two electromagnetic windings 314—316, 318—320, 322—324 and 326—328, respectively, which are disposed to be connected under predetermined conditions to a source of supply of electrical energy represented by the conductors 330 and 332.

Thus the winding 314 of the control valve 306 is disposed to be connected across the supply conductors 330 and 332 by conductors 334 and 336 when a manually operated switch 338 is actuated to a circuit establishing position. The other winding 316 of the control valve 306 is disposed to be energized when a limit switch 340 is actuated by an adjustable stop member 342 which is carried on the end of the frame 194 to establish a circuit which extends from conductor 330 through conductor 344, limit switch 340, conductor 346, winding 316

75 and conductor 336 to the other conductor 332 of the source of supply of energy.

The winding 318 of the control valve 308 is disposed to be energized when a limit switch 348 is actuated as will be described hereinafter to establish a circuit which extends from conductor 330 of the source of energy through conductors 350 and 352, the limit switch 348, conductor 354, winding 318 and conductor 356 to the other conductor 332 of the source of supply. Likewise 10 the winding 320 of the control valve 308 is disposed to be energized when a limit switch 358 is actuated to a circuit establishing position as will be described herein- 15 after to establish a circuit which extends from the conductor 330 of the source of supply through conductor 350, limit switch 358, conductor 360, winding 320 and conductor 356 to the other conductor 332 of the source of supply.

The winding 322 of the control valve 310 is disposed to be energized when a limit switch 362 is actuated to 20 a circuit establishing position as will be described herein- 25 after to establish a circuit which extends from conductor 330 of the source of supply through conductors 350, 364, limit switch 362, conductor 366, winding 322 and conductor 368 to the other conductor 332 of the source of supply of energy. Likewise the winding 324 of the control valve 310 is disposed to be energized when another limit switch 370 is actuated to a circuit establishing position as will be described herein- 30 after to establish a circuit which extends from conductor 330 of the source of supply through conductors 350, 364 and 372, limit switch 370, conductor 374, winding 324 and conductor 368 to the other conductor 332 of the source of supply.

As illustrated, the winding 326 of the control valve 312 35 is also disposed to be energized when a limit switch 376 is actuated to a circuit establishing position as will be described hereinafter to establish a circuit which extends from the conductor 330 from the source of supply through conductors 350 and 364, limit switch 376, conductor 378, winding 326 and conductor 380 to the other conductor 332 of the source of supply. In a similar manner winding 328 of the control valve 312 is disposed to be energized when a limit switch 382 is actuated to a circuit establishing position, as will be described herein- 40 after, to establish a circuit which extends from conductor 330 through conductors 350 and 352, limit switch 382, conductor 384, winding 328 and conductor 380 to the other conductor 332 of the power source.

As illustrated, the ring retaining member 58 of one of the rotatable housings is provided with four spaced lugs 386 thereabout, such lugs being 90° apart. The spaced lugs 386 are, in effect, timing lugs for controlling the actuation of the limit switches 358 and 348—382. Thus the limit switch 358 is connected to a limiting member 388 disposed in the path of movement of the timing lugs 386 so that when engaged thereby the limiting member 388 actuates the limit switch 358 to a circuit establishing position. In a similar manner the limit switch 348 and limit switch 382 are disposed to be simultaneously actuated by the timing lugs 386 in that the limit switches 348 and 382 are commonly connected to a limiting member 390 which is also disposed in the path of movement of the spaced timing lugs 386 to be engaged thereby under predetermined movements of the ring retaining member 58 as the billet 40 is rotated.

The limit switches 362 and 376 are also disposed to be simultaneously actuated by means of an adjustable stop member 392 which is carried by the upright pivotal frame 198 upon predetermined pivotal movement of the frame in a clockwise direction. In a similar manner the limit switch 370 is disposed to be actuated to a circuit establishing position when engaged by an adjustable stop member 394 which is also carried by the pivotal frame 198 upon predetermined movement of the frame in a counterclockwise direction.

In operation, assuming that a billet 40 has been supplied to one end of the billet grinding device 10 and fed through the rotatable housings 42 and 44, for example, of the fixed housing 16, to a point where the end of the billet 40 is positioned beneath the grinding wheel 38 which is normally held in a position retracted from an engaging position after a grinding operation, as will be referred to hereinafter, and assuming that the motor 232 has been energized to drive the grinding wheel 38, then in order to actuate the grinding wheel 38 into engagement with a surface of the billet 40 the manually operated switch 338 is operated to a circuit establishing position to energize the winding 314 of the control valve 306. When thus energized the control valve 306 permits the application of fluid pressure through the conduit represented by the dash arrow line 290 to the double acting cylinder 244 to apply a constant pressure thereto and effect an upward movement of the piston rod 240 thereof to effect a counterclockwise movement of the frame 194 about its pivot 196 to lower the grinding wheel 38 into grinding engagement with the billet 40 and apply a constant pressure though such grinding wheel. Assuming that the grinding wheel 38 is in engagement with the billet 40 adjacent a corner or edge thereof in the position illustrated in Fig. 6, and that one of the pins 186 or 188 is in a position to begin to engage a slot of the Geneva gear 174, the frame 198 would normally be in the position illustrated in which the stop member 392 has actuated the limit switches 362 and 376 to effectively energize windings 322 and 326 of the control valves 310 and 312, respectively, whereby the cylinders 260 and 272 are under pressure to drive their piston rods 258 and 278 outwardly therefrom and tend to drive the frame 198 in a counterclockwise direction about its pivot 200. Such movement of the frame 198, however, is prevented since the roller stop 286 actuated by the cylinder 272 is in the path of movement of the stop 288 to prevent such counterclockwise movement of the frame 198. Under such conditions no lateral movement of the grinding wheel 38 is effected.

As one of the pins 186 or 188 engages a slot of the Geneva gear 174, movement of the retaining ring 58 is effected simultaneously with the movement of the billet 40 whereby the timing lug 386 adjacent the limiting member 388 is actuated to engage such limiting member as the rotatable movement of the billet 40 is effected. Under such conditions the limit switch 358 is actuated to a circuit closing position to effect the energization of the winding 320 of the control valve 308 to effect an instantaneous release of fluid pressure applied to the cylinder 246 whereby only the constant pressure applied by the cylinder 244 is maintained on the grinding wheel 38 as the rotation of the billet is effected. Thus the grinding wheel will ride up over the corner of the billet 40 with only the constant pressure maintained thereon to effect the grinding of the corner of the billet as the billet is turned thereunder. As the billet is turned through its quarter revolution, the grinding wheel then rotates down the flat surface of the billet to a position closely approximating that shown in Fig. 6 of the drawing, at which position the timing lug 386 has been advanced to engage the limiting member 390 to effect the simultaneous operation of the limit switches 348 and 382 as the billet approaches a position where only a flat surface is presented to the grinding wheel 38. Thus the first pass of the grinding wheel over the flat surface of the billet presented thereto as the quarter turn rotation of the billet is completed is performed only under the constant pressure as applied by the cylinder 244, but as the billet approaches the flat position shown in the drawing, the limit switch 348 is actuated to complete the energizing circuit for winding 318 of the valve 308 to supply fluid pressure to the cylinder 246 whereby additional pressure is applied to the frame 194 over that of the constant pressure of the cylinder 244 to, in effect, apply additional pressure

through the grinding wheel 38. At the same time the limit switch 382 is actuated to energize the winding 328 of the control valve 312 to effectively relieve the pressure applied to the double acting cylinder 272 and effect an operation thereof to withdraw the roller stop 286 from the path of movement of the adjustable stop 288. Thus under the pressure of the cylinder 260, the pressure of which has been applied thereto when the winding 322 was initially energized, the piston rod 258 moves outwardly therefrom to effect a counterclockwise movement of the frame 198 to move the grinding wheel 38 laterally across the flat surface of the billet 40 to the corner which has just been ground until the stop 394 engages and actuates the limit switch 370 to energize the winding 324 of the control valve 310, it being noted that limit switches 362 and 376 have been actuated to the open circuit position in such operation. When the winding 324 is thus energized to release the pressure applied to the double acting cylinder 260, the piston rod 258 is actuated to effect a clockwise pivotal movement of the frame 198 to effect a lateral movement of grinding wheel 38 across the flat surface of the billet 40 toward the next corner which is to be ground. As such pivotal movement of the frame 198 is effected and the grinding wheel 25 approaches the next corner of the billet to be ground, the stop 392 engages and actuates the limit switch 362 and limit switch 376 to again establish the energizing circuits for windings 322 and 326, respectively, of the control valves 310 and 312, respectively, to again effect an operation of the roller stop 286 into the path of movement of the stop member 288 to prevent pivotal movement of the frame 198 and simultaneously therewith effect an application of pressure to the cylinder 260 to tend to move the frame member 198 in a counterclockwise movement, which movement is effectively stopped by the roller stop 286. Thus, in effect, the flat surface of the billet 40 is subjected to three grinding operations for each grinding operation of an associated corner. The cycle just described is repeated in effecting the grinding of each corner and the following flat surface, it being noted that the grinding is progressive as the billet 40 passes through the housings 16 and 18. During such grinding movement it is to be noted that spring members 228 and 230 permit a slight amount of sideways movement of the grinding wheel 38 as the grinding wheel is moved laterally across the flat surface of the billet 40. Such slight sideways movement has been found to effect an efficient grinding of the flat surface of the billet as the grinding wheel moves laterally thereacross.

In operation it is found that where the grinding wheel 38 has a size of about $2\frac{1}{2}$ inches across the grinding face thereof, a progressive grinding of the surface of the billet is obtained in a somewhat spiral fashion about the flat surface and corners of the billet. An overall elapsed time of about two seconds is required for making the three passes on the flat surface, the Geneva gear being designed to permit about two seconds also on each of the corners. In practice it is preferred that the billets be of from five to nine feet in length with a size of up to $5\frac{1}{2}$ inches square or larger. It will be appreciated that as the size of the billet varies, different Geneva gear movements can be utilized so as to correlate the quarter turn rotation of the billet with the time required to grind the corners and flat surfaces thereof. The billets are effectively ground, it being noted that as the square billet is ground, the square shape of the initial billet is maintained. As will be appreciated, since the rotatable housings 42 and 44 are provided with suitable feed rolls or grooved wheel member 88, the billet grinding apparatus 10 can readily accommodate billets which are not perfectly straight, the adjustable grooved wheel members of the rotatable housings 42 and 44 being automatically slightly displaced while holding the billet by opposite edges thereof in the cooperating grooves of the opposite wheels of each pair to accommo-

date any misalignment or irregularities which might be had in the surface of the billet.

In practice billets are usually fed continuously to the billet grinding apparatus 10 so that as one billet is ground the forward end of another billet is immediately engaged by the grinding wheel 38. If, however, discontinuous operation is had, then when the grinding of a billet is completed the grinding wheel 38 drops below the level of the billet 40 as the end of the billet passes therebeyond with the result that the stop member 342 carried by the frame 194 actuates the limit switch 340 to establish the energizing circuit to the winding 316 of the control valve 306. When thus energized, the control valve 306 releases the constant pressure applied to the cylinder 244 to effect an operation thereof to retract the piston rod 240 and effect a clockwise movement of the frame 194 about its pivot 196 to raise the grinding wheel 38 to a position above the normal position of a billet so that the grinding wheel 38 will then be in a raised position disposed to be actuated into engagement with the next succeeding billet when the manually operated switch 338 is moved to its circuit establishing position.

The billet grinding apparatus of this invention is outstanding in its operation in that it effectively accomplishes a complete grinding of not only the flat surfaces but also the corners of a billet, such grinding being progressive as the billet is rotatably advanced through the billet grinding apparatus. In operation the billet grinding apparatus is fast and efficient, billets having a nine-foot length being readily ground in a period of time as short as six minutes, depending upon the timing cycle determined by the size of the Geneva gear included in the drive for the apparatus. The controls are such that the grinding pressure applied to all external portions of a billet being conditioned is controlled with the corners being ground in substantially the same amount of time as the flat surfaces of the billet. By providing for the lateral movement of the grinding wheel relative to the flat surfaces of the billet, burning of the metal is prevented and the entire flat surface is contacted.

The apparatus of this invention saves untold money over the investment required with previously used swing grinders as well as considerable savings in manpower, as one man can operate this billet grinder apparatus in a continuous fashion, it being noted that once the operation is started it is automatic throughout a grinding cycle until an end of a billet passes the grinding wheel. Thus one man can feed succeeding billets to the grinding machine, walk to the other end and see that the ground billet is discharged properly therefrom, this being the only work involved once the apparatus has been set into operation and billets are fed continuously thereto.

We claim:

1. In a billet grinding apparatus, the combination comprising, a pair of fixed spaced housings, a rotatable housing carried by each of the fixed spaced housings and having an opening therethrough disposed in aligned relation with one another for receiving a billet, a pair of grooved wheel members carried by each of the rotatable housings in a predetermined spaced relation with the grooves of each pair facing and aligned with one another for receiving and supporting a billet therebetween, means interconnected between the rotatable housings disposed to be operated to effect a simultaneous rotation of the rotatable housings, means disposed to be operated by the rotation of the rotatable housings and connected to the wheel members thereof for effecting a simultaneous drive of the wheel members, the drive of the wheel members and the rotation of the rotatable housings cooperating to rotatably advance a billet through the aligned openings of the rotatable housings, grinding means positioned between the fixed spaced housings disposed for controlled lateral and vertical movements relative to the sides and corners of a billet to engage and progressively

75

grind the surface of a billet as the billet is rotatably advanced through the aligned openings of the rotatable housings, means connected to intermittently drive the interconnected means to control the operation thereof and effect an intermittent drive of the rotatable housings and the grooved wheel members carried thereby to intermittently effect a quarter turn of the billet, and control means responsive to the intermittent turning of the billet for effecting a positive lateral grinding movement of the grinding means on a side of the billet as the billet is stationary between each intermittent quarter turn of the billet.

2. In a billet grinding apparatus, the combination comprising, a pair of fixed spaced housings, a rotatable housing carried by each of the fixed spaced housings and having an opening therethrough disposed in aligned relation with one another for receiving a billet, a pair of grooved wheel members carried by each of the rotatable housings in a predetermined spaced relation with the grooves of each pair facing and aligned with one another for receiving and supporting a billet therebetween, means interconnected between the rotatable housings disposed to be operated to effect a simultaneous rotation of the rotatable housings, means disposed to be operated by the rotation of the rotatable housings and connected to the wheel members thereof for effecting a simultaneous drive of the wheel members, the drive of the wheel members and the rotation of the rotatable housings cooperating to rotatably advance a billet through the aligned openings of the rotatable housings, grinding means positioned between the fixed spaced housings disposed for controlled lateral and vertical movements relative to the sides and corners of a billet to engage and progressively grind the surface of a billet as the billet is rotatably advanced through the aligned openings of the rotatable housings, means connected to intermittently drive the interconnected means to control the operation thereof and effect an intermittent drive of the rotatable housings and the grooved wheel members carried thereby to intermittently effect a quarter turn of the billet, and control means responsive to the intermittent rotation of the billet for controlling the pressure of the grinding means on the flat surfaces and edges of the billet, said control means including means to prevent a positive lateral movement of the grinding means as the billet is rotatably advanced a quarter turn through the housings and means to effect a positive lateral movement of the grinding means on a side of the billet as the billet is stationary between each intermittent quarter turn of the billet.

3. In a billet grinding apparatus, the combination comprising, a pair of fixed spaced housings, a pair of spaced rotatable housings carried by each of the fixed spaced housings and having openings therethrough disposed in aligned relation with one another for receiving a billet, a pair of grooved wheel members carried by each of the rotatable housings in predetermined spaced relation with the grooves of each pair of wheel members facing and aligned with one another for receiving and supporting a billet having a substantially square cross section and a longitudinal axis therebetween, means interconnected with each pair of the rotatable housings disposed to be operated to effect a simultaneous rotation of each of the rotatable housings, drive means for the wheel members disposed to be operated as the rotatable housings are rotated to effect a simultaneous drive of each of the wheel members carried thereby, the rotation of the rotatable housings effecting a rotation of the spaced grooved wheel members about the longitudinal axis of a billet supported therein and cooperating with the drive of the grooved wheel members to rotatably advance a billet through the aligned openings of the rotatable housings, grinding means positioned between the fixed spaced housings disposed for controlled lateral and vertical movements relative to the sides and corners of a billet to engage and progressively grind the flat surfaces

and corners of a billet as the billet is rotatably advanced through the aligned openings of the rotatable housings, means connected to intermittently drive the interconnected means for effecting a predetermined intermittent drive of the rotatable housings and the grooved wheel members carried thereby to intermittently effect a quarter turn of the billet, and control means responsive to the intermittent driving of the rotatable housings and the turning of the billet for preventing a positive lateral movement of the grinding means during a turning movement of the billet and for effecting a positive lateral movement of the grinding means across a side of the billet between each intermittent quarter turn thereof.

4. In a billet grinding apparatus, the combination comprising, a pair of fixed spaced housings, a rotatable housing carried by each of the fixed spaced housings and having an opening therethrough disposed in aligned relation with one another for receiving a billet, a pair of grooved wheel members carried by each of the rotatable housings in a predetermined spaced relation with the grooves of each pair facing and aligned with one another for receiving and supporting a billet therebetween, means interconnected between the rotatable housings disposed to be operated to effect a simultaneous rotation of the rotatable housings, means disposed to be operated by the rotation of the rotatable housings and connected to the wheel members thereof for effecting a simultaneous drive of the wheel members, the drive of the wheel members and the rotation of the rotatable housings cooperating to rotatably advance a billet through the aligned openings of the rotatable housings, grinding means positioned between the fixed spaced housings disposed to engage and progressively grind the surfaces of a billet as the billet is rotatably advanced through the aligned openings of the rotatable housings, means connected to intermittently drive the interconnected means to control the operation thereof and effect an intermittent drive of the rotatable housings and the grooved wheel members carried thereby to rotate the billet a quarter turn and present a flat surface thereof to the grinding means, and control means responsive to the intermittent drive of the rotatable housings and turning of the billet disposed to be operated upon completion of said quarter turn rotation to effect a positive lateral movement of the grinding means across said flat surface of the billet, said control means including means disposed to prevent a positive lateral movement of the grinding means during said quarter turn rotation of the billet.

5. In a billet grinding apparatus having means for rotatably advancing a billet therethrough to be engaged by a grinding means and having operating means for effecting an intermittent quarter turn rotation of the billet to progressively present the flat surfaces and corners thereof to be engaged by the grinding means, the combination comprising, a frame support for the grinding means, the support being pivotally mounted and disposed for movement to effect lateral and vertical movements of the grinding means relative to the billet when the grinding means is in engagement therewith, a first actuating means connected to the grinding means support and disposed to be operated to effect a pivotal movement of the support to move the grinding means laterally across a flat surface of the billet, a second actuating means connected to the grinding means support disposed to be operated to impose a constant grinding pressure on the grinding means, a third actuating means connected to the grinding means support disposed to be operated to impose additional grinding pressure on the grinding means, a fourth actuating means disposed to be operated to actuate a stop into and out of the path of movement of the grinding means support, a first and second limit switch means disposed to be simultaneously operated to circuit establishing positions as a quarter turn rotation of the billet is completed to present a flat surface thereof to the grinding means and to

circuit interrupting positions during a quarter turn rotation of the billet to present a corner thereof to the grinding means, the first and second limit switch means being connected to effect the simultaneous operation of the fourth and third actuating means when in circuit establishing positions to actuate the stop out of the path of movement of the grinding means support and to apply said additional pressure to the grinding means, a third limit switch means disposed to be operated to circuit establishing position as a quarter turn rotation of the billet is initiated to present a corner thereof to the grinding means to effect an operation of the third actuating means to remove the additional grinding pressure from the grinding means, a fourth limit switch means disposed to be operated to a circuit establishing position by a predetermined lateral movement of the grinding means in the one direction and connected to the first actuating means to reverse the operation thereof to effect a pivotal movement of the support to move the grinding means laterally in a reverse direction, and a fifth and sixth limit switch means disposed to be simultaneously operated to circuit establishing positions by a predetermined lateral movement of the grinding means in said reverse direction, the fifth limit switch being connected to effect the operation of the fourth actuating means to move the stop into the path of movement of the grinding means support, the sixth limit switch being connected to effect the operation of the first actuating means to effect a pivotal movement of the support to move the grinding means in a direction opposite to said reverse direction, and a seventh limit switch means disposed to be operated upon completion of the grinding of a billet to effect an operation of the second actuating means to release the constant pressure on the grinding means and raise the grinding means out of a billet engaging position.

6. In a billet grinding apparatus having means for rotatably advancing a billet therethrough to be engaged by a grinding means and having operating means for effecting an intermittent quarter turn rotation of the billet to progressively present the flat surfaces and corners thereof to be engaged by the grinding means, the combination comprising, a frame support for the grinding means, the support being pivotally mounted and disposed for movement to effect lateral and vertical movements of the grinding means relative to the billet when the grinding means is in engagement therewith, a first actuating means connected to the grinding means support and disposed to be operated to effect a pivotal movement of the support to move the grinding means laterally, a second actuating means connected to the grinding means support disposed to be operated to effect a pivotal movement of the support to effect a vertical movement of the grinding means, a third actuating means connected to the grinding means support disposed to be operated to apply grinding pressure to the grinding means, a stop disposed to be actuated into and out of the path of movement of the grinding means support, a fourth actuating means connected to effect movement of the stop, a first and second limit switch means disposed to be simultaneously operated to circuit establishing positions as the billet completes a quarter turn rotation to present a flat surface thereof to the grinding means, the first limit switch means being connected when in the circuit establishing position to effect the operation of the fourth actuating means to move the stop out of the path of movement of the grinding means support, the second limit switch means being connected when in the circuit establishing position to effect operation of the third actuating means to apply grinding pressure to the grinding means, a third limit switch means disposed to be operated to a circuit establishing position by lateral movement of the grinding means in the one direction and connected to the first actuating means to reverse the operation thereof and effect a pivotal movement of the support to move the grinding means

laterally in a reverse direction, a fourth and fifth limit switch means disposed to be simultaneously operated to circuit establishing positions by a predetermined lateral movement of the grinding means in said reverse direction, the fourth limit switch means being connected when in the circuit establishing position to the third actuating means to effect the operation thereof to release said grinding pressure, the fifth limit switch means being connected when in the circuit establishing position to the fourth actuating means to move the stop into the path of movement of the grinding means support, a sixth limit switch means disposed to be operated to a circuit establishing position as a quarter turn rotation of the billet is initiated to present a corner thereof to the grinding means to effect operation of the third actuating means to release the grinding pressure applied thereby, and a seventh limit switch means disposed to be operated upon completion of a grinding operation to effect an operation of the second actuating means to raise the grinding means to a position above the grinding position.

7. In a billet grinding apparatus, the combination comprising, a pair of fixed spaced housings, a rotatable housing carried by each of the fixed spaced housings and having an opening therethrough disposed in aligned relation with one another for receiving a billet, a pair of wheel members carried by each of the rotatable housings in a predetermined spaced relation with the faces of the wheel members aligned with one another for receiving and supporting a billet therebetween, means interconnected between the rotatable housings disposed to be operated to effect a simultaneous rotation of the rotatable housings, means disposed to be operated by the rotation of the rotatable housings and connected to the wheel members thereof for effecting a simultaneous drive of the wheel members, the drive of the wheel members and the rotation of the rotatable housings cooperating to rotatably advance a billet through the aligned openings of the rotatable housings, grinding means positioned between the fixed spaced housings disposed for controlled lateral and vertical movements relative to the sides and corners of a billet to engage and progressively grind the surface of a billet as the billet is rotatably advanced through the aligned openings of the rotatable housings, means connected to intermittently drive the interconnected means to control the operation thereof and effect an intermittent drive of the rotatable housings and the spaced wheel members carried thereby to intermittently effect a quarter turn of the billet, and control means responsive to the inter-

mittent drive of the rotatable housings and turning of the billet for preventing a positive lateral movement of the grinding means during a turning movement of the billet and for effecting a positive lateral movement of the grinding means across a side of the billet between each intermittent quarter turn thereof.

8. In a billet grinding apparatus, the combination comprising, a pair of fixed spaced housings, a pair of spaced rotatable housings carried by each of the fixed spaced housings and having openings therethrough disposed in aligned relation with one another for receiving a billet, a pair of wheel members carried by each of the rotatable housings in a predetermined spaced relation with the faces of the wheel members of each pair aligned with one another for receiving and supporting a billet therebetween, means interconnected with each pair of the rotatable housings disposed to be operated to effect a simultaneous rotation of each of the rotatable housings, drive means for the wheel members disposed to be operated as the rotatable housings are rotated to effect a simultaneous drive of each of the wheel members carried thereby, the drive of the wheel members and the rotation of the rotatable housings cooperating to rotatably advance a billet through the aligned openings of the rotatable housings, grinding means positioned between the fixed spaced housings disposed for controlled lateral and vertical movements relative to the sides and corners of a billet to engage and progressively grind the surface of a billet as the billet is rotatably advanced through the aligned openings of the rotatable housings, means connected to intermittently drive the interconnected means to control the operation thereof and effect an intermittent drive of the rotatable housings and the wheel members carried thereby to intermittently effect a quarter turn of the billet, and control means responsive to the intermittent drive of the rotatable housings and turning of the billet for preventing a positive lateral movement of the grinding means during a turning movement of the billet and for effecting a positive lateral movement of the grinding means across a side of the billet between each intermittent quarter turn thereof.
